MODULATING SYSTEM

Raymond E. Meyer, Fort Wayne, Ind., assignor to
Farnsworth Television and Radio Corporation,
a corporation of Delaware

Application June 14, 1943, Serial No. 490,752

2 Claims. (Cl. 179—171.5)

This invention relates to modulating systems and particularly to apparatus for stabilizing the frequency of an amplitude modulated wave.

According to conventional practice, a frequently employed means for modulating a carrier wave in amplitude in accordance with a modulating signal comprises a grid modulated power amplifier arranged for so-called class C operation. In such a system the grids of the power amplifier tube are coupled to a carrier wave generator for excitation thereby. The grid circuits also are provided with a relatively large negative bias so that grid current flows only during portions of the alternating current cycles of the carrier wave. The time during which the grid current flows is controlled by the strength of the modulating signal. The flow of grid current in the power amplifier results in a power drain upon the carrier wave generator which varies in proportion to the strength of the modulating signal.

As is well known in the art, however, the power drain upon a carrier wave generator such as an oscillator is reflected into the frequency determining circuit thereof. Such reflection is manifested in this circuit as a resistance. Consequently, a variation in the energy derived from the carrier wave generator effects a variation in the effective resistance of the frequency determining circuit. The frequency of a tuned circuit is given exactly by the equation

$$f = \frac{1}{2\pi\sqrt{LC}} \left(\sqrt{1 - \frac{1}{Q^2}} \right)$$

where

$$Q = \frac{2\pi f L}{r}$$

r being the effective resistance in such a tuned circuit. Since the frequency of the carrier wave is thus a function of the resistance of the frequency determining circuit, a variation in the effective resistance of this circuit produces a corresponding variation in the frequency of the generated carrier wave. Thus, in the output circuit of the grid modulated power amplifier there appears a carrier wave which is modulated, not only in amplitude as desired, but also in frequency. The latter type of modulation is undesirable and in some cases may be so great as to render the operation of the system unsatisfactory.

It is an object of the present invention, therefore, to provide, in an amplitude modulating system, means controlled by the modulating signal for preventing frequency modulation of the carrier wave.

Another object of the invention is to provide

means for loading a carrier wave generator to compensate for the loading of the generator by a grid modulated power amplifier, whereby to maintain a constant load on the generator.

5 In accordance with the present invention, there is provided a carrier wave generator and means for deriving energy therefrom for excitation purposes which is directly proportional to a modulating signal. There also is provided a means 10 for deriving additional energy from the generator which is inversely proportional to the modulating signal. Thus, the load which is placed upon the carrier wave generator by the derivation therefrom of the two portions of energy is maintained constant.

More specifically, in accordance with the embodiment of the invention illustrated herein, there is coupled to the generator the input circuit of a power amplifier. There also is connected to 20 the input circuit of the power amplifier a modulating signal, whereby to vary the amount of energy derived from the generator to drive the power amplifier in accordance with this signal. Additionally, there is provided a variable compensating load circuit which also is coupled to the carrier wave generator. The energy which is derived from the generator by the compensating load circuit is controlled by the modulating signal. However, the modulating signal is 25 connected to the compensating load circuit in phase opposition to its connection to the power amplifier. Thus, the energies derived from the generator by the power amplifier and the compensating load circuit are in phase opposition in 30 these two circuits so that a constant load is maintained on the generator.

For a better understanding of the invention, together with other and further objects thereof, reference is had to the following description, 40 taken in connection with the accompanying drawing, and its scope will be pointed out in the appended claims.

In the accompanying drawing:
Fig. 1 is a circuit diagram of one embodiment 45 of the invention; and,

Fig. 2 is a graphical representation of the energy components derived from the carrier wave generator which will be referred to in the explanation of the operation of the disclosed circuit.

50 Referring now more particularly to Fig. 1 of the drawing, there is shown a carrier wave generator 11 which, for example, may be any conventional type of oscillator. A parallel tuned circuit comprising an inductor 12 and a condenser

13 is connected to the output terminals of the generator. The parameters of this circuit are adjusted to effect resonance of the circuit at the frequency of the generator.

An inductor 14 is coupled to the generator inductor 12 and its terminals are connected to the control grid electrodes of a twin triode electron discharge device 15. A condenser 16 also is connected to the terminals of the inductor 14, whereby to tune the parallel circuit so formed for resonance at the frequency of the carrier wave generator 11. The anodes of the vacuum tube 15 are connected to a parallel resonant circuit including a condenser 17 and an inductor 18. This circuit also is tuned for resonance at the frequency of the generator 11. A coil 19 is coupled inductively to the inductor 18 and is connected to the terminals 21 of an output circuit. The tube 15 and its associated input and output circuits comprise a power amplifier. Conventional neutralization (not shown) of the power amplifier preferably is employed but has been omitted in order to simplify the drawing.

There also is provided an inductor 22 which is coupled to the generator inductor 12. A tuning condenser 23 is connected to the terminals of the inductor 22, whereby to effect resonance of the parallel circuit so formed at the frequency of the generator 11. The terminals of the inductor 22 are connected to the anodes of a double diode 24.

A source of modulating signal 25 is connected to the input circuits of the tube 15 and also of the diode 24. The connection of the modulating signal source to the grids of the tube 15 includes a source of negative biasing potential such as a battery 26, whereby the tube is arranged for so-called class C operation. The connection of the modulating signal source 25 to the diode 24 is in phase opposition to the connection of this source to the amplifier tube 15.

Space current for the amplifier tube 15 and the carrier wave generator 11 is supplied from a source of direct current potential such as a battery 27. These connections are made by way of center taps on the inductors 12 and 18.

Referring now to the operation of the apparatus described, consider first the manner in which the amplitude modulation of the carrier wave is effected. The grids of the tube 15 are excited at the carrier wave frequency by means of energy derived from the carrier wave generator 11 through the coil 14. The amount of energy so derived is determined by the modulating signal supplied from the source 25. For the purposes of this explanation, assume that the wave form of the modulating signal is sinusoidal. When such a signal is applied to the grids of the tube 15 the bias thereof varies sinusoidally, and, depending upon the instantaneous amplitude of the signal, the grids of the tube draw varying amounts of current through the coil 14. This places a load upon the carrier wave generator 11 which varies sinusoidally.

In Fig. 2, the solid line curves 28 represent the variation of the carrier wave energy which is derived from the generator 11 as the modulating signal varies sinusoidally. The average power which is supplied by the generator to the power amplifier over a period of time is represented by "A." However, by reason of the continuous variation of the power supplied by the generator there is reflected into the output circuit thereof a continuously varying resistance. If it were not for the stabilizing arrangement provided in ac-

cordance with this invention, this varying resistance would effect a variation in the frequency of the carrier wave generated.

However, there is provided in accordance with the present invention the compensating load circuit including the coil 22 and the diode 24. The energy derived from the generator 11 for this circuit is determined by the conductivity of the tube 24. The conductivity of this tube is controlled by the modulating signal from the source 25. Thus, in the assumed case of a sinusoidal modulating signal, the conductivity of the tube 24 and the energy derived from the generator 11 varies sinusoidally. But in the case of this circuit, it is to be noted that the modulating signal is applied to the diode 24 in phase opposition to the application thereof to the amplifier tube 15. Thus, as the energy supplied through the coil 14 is increasing, the energy supplied through the coil 22 is decreasing correspondingly.

This relation may be observed by referring to Fig. 2 wherein the broken line curves 29 represent the envelope of the carrier frequency energy which is derived from the generator 11 by the coil 22 and the diode 24. It is seen that these curves 25 are displaced 180 electrical degrees from the curves 28. By suitable adjustment of the diode circuit parameters, the maximum and minimum amplitudes of the curves 29 may be made equal to corresponding amplitudes of the curves 28. In this case the average power supplied by the generator 11 to the compensating load circuit including the diode 24 is represented by "A," also. However, the instantaneous amplitudes of the curves 29 are continuously varying in phase opposition to the variations of the instantaneous amplitudes of the curves 28. The respective instantaneous amplitudes at all times are mutually complementary so that the total energy derived from the generator is maintained constant. The total energy supplied by the generator is represented at "B."

As a consequence of this arrangement, the tendency produced by the derivation of the varying amounts of power by the power amplifier to effect resistance variations in the frequency determining circuit of the generator 11 is counteracted by a similar tendency in an opposite sense to produce resistance variations by the derivation of varying amounts of power by the compensating load circuit.

Thus, there is produced a result whereby to effect a complete cancellation of the effects which would produce resistance changes in the output circuit of the carrier wave generator 11. As a consequence, the effective resistance of this circuit is maintained constant, whereby the frequency of the carrier wave also is maintained constant in so far as such frequency is dependent upon the effective resistance.

While there has been described what, at present, is considered the preferred embodiment of the invention, it is obvious to those skilled in the art that various changes and modifications may be made therein without departing from the invention, and therefore, it is aimed in the appended claims to cover all such changes and modifications as fall within the true spirit and scope of the invention.

What is claimed is:

1. In a modulating system, a carrier wave generator, a power amplifier including an electron discharge device having a pair of control grids, means for coupling inductively said control grids to said generator for excitation thereby, a com-

pensating load circuit including a full wave rectifier, means for coupling inductively said rectifier to said generator, and a source of modulating signal connected to the input circuits of said electron discharge device and said rectifier in phase opposition, said modulating signal serving to grid-modulate said power amplifier and simultaneously to control conduction in said rectifier, whereby to maintain a constant load on said generator.

2. In a modulating system, a carrier wave generator, a power amplifier including an electron discharge device having a pair of control grids,

means including a coil for coupling inductively said control grids to said generator for excitation thereby, a compensating load circuit including a full wave rectifier, means including a second coil for coupling inductively said rectifier to said generator, and a source of modulating signal connected to the input circuits of said electron discharge device and said rectifier in phase opposition, said modulating signal serving to grid-modulate said power amplifier and simultaneously to control conduction in said rectifier, whereby to maintain a constant load on said generator.

RAYMOND E. MEYER.
